WILLIAM H. DILWORTH. [L. S.]

UNITED STATES PATENT OFFICE.

WILLIAM H. DILWORTH, OF HOBOKEN, NEW JERSEY.

DESIGN FOR A FRUIT-JAR.

SPECIFICATION forming part of Design No. 16,817, dated July 27, 1886.

Application filed May 27, 1886. Serial No. 203,474. Term of patent 7 years.

To all whom it may concern:

Be it known that I, WILLIAM H. DILWORTH, a citizen of the United States, residing at Hoboken, in the county of Hudson and State of New Jersey, have invented and produced a new and original Design for Fruit-Jars, of which the following is a specification, reference being had to the accompanying drawing, forming part thereof.

10 My invention consists in a new and original design for fruit-jars and the like, the said design being fully described in the following specification and illustrated in the accompanying drawing, which represents an elevation thereof.

15 In the drawing, the letter A designates the body of a fruit-jar embodying my design, such jar being shown as circular in cross-section. The neck a is curved in an ogee shape, and a projection or rib, b, is near the end of such neck. A Greek border, B, extends about the jar near its bottom, and a second border, B', of the same design, encircles the jar at the juncture of the body and neck. A screw-cap, C, having a knurled or wrinkled head, c, is shown as closing the jar, and a curved wire bail, D, extends from said cap, and a handle, D', of cylindrical form, is on said bail.

20 It will be observed that the Greek borders B B' vary in their contour lines from the ordinary border by having a broken portion or

section, b', in each square, whereby the artistic effect is heightened.

The Greek border shown consists of a band upon which is displayed, preferably in relief, 35 the figure shown, composed of the line or bar a', winding along the band, its angles being all right angles, or substantially so, and forming the broken portion b', as described.

What I claim as new, and desire to secure 40 by Letters Patent, is—

1. The design for a fruit-jar herein described, which consists in a body, an ogee-shaped neck, and a Greek border, as set forth.

2. The design for a fruit-jar herein de- 45 scribed, which consists in a body, an ogee-shaped neck, the Greek borders on said body, the projection on the said neck, and the cap and handle, designed as described and shown.

3. The design for a fruit-jar herein de- 50 scribed, which consists in a body provided with an ogee-shaped neck, and the Greek borders on the body having broken portions or sections b', as set forth.

In testimony whereof I have hereunto set 55 my hand and seal in the presence of two subscribing witnesses.

WILLIAM H. DILWORTH. [L. S.]
